UNITED STATES PATENT OFFICE

HENRY H. DEWEY, OF CLEVELAND, OHIO.

CORNER-STAY.

No. 826,523.

Specification of Letters Patent.

Patented July 10, 1906.

Application filed February 20, 1905. Serial No. 246,443.

To all whom it may concern:

Be it known that I, HENRY H. DEWEY, residing at Cleveland, in the county of Cuyahoga and State of Ohio, have invented a certain new and useful Improvement in Corner-Stays, of which the following is a full, clear, and exact description, reference being had to the accompanying drawings.

My invention relates to corner-stays for boxes or trunks and the like, and particularly stays constructed of sheet metal, and has for its object the construction of a device of this character that will dispense with the necessity for dovetailing or beveling the ends and sides of the box, that will rigidly support the ends and sides against displacement, and that will combine facility of application to the box sides and ends with strength and simplicity of construction.

Generally speaking, my invention may be defined as consisting of the combinations of elements embodied in the claims hereto annexed.

Referring to the drawings, Figure 1 represents a perspective view of the corner of a box, showing applied thereto a stay constructed in accordance with my invention. Fig. 2 represents a perspective view of such a stay. Fig. 3 represents a sectional view of such stay, taken on the line 3-3 of Fig. 2; and Fig. 4 represents a similar view of a modification of the stay shown in the preceding figures.

The stay 1 consists of an outer member and an inner member made of sheet metal, preferably galvanized sheet-steel. The outer member is bent to form two flat side portions or plates 2, the planes of which are at right angles to each other. Each of the plates 2 is provided with an inwardly-projecting longitudinal rib 3, adapted to fit into a corresponding rabbet or recess in the outer surface of the adjacent end 4 and side 5 of the box to which it is applied. Outside said rib are holes 10 for securing the plates to the box. The corner or apex of said outer member is bent inwardly to form a reentrant angle 6, the sides 7 of said angle being bent at right angles to the planes of the side portions 2. The lengths of the sides 7 are governed by the thickness of the material of which the box is made. Secured to and within said outer member is an inner member comprising flat side portions or plates 8, bent at right angles to each other. To secure said members together, I cut through each of the plates

8 from a point between the edge thereof and the apex of the inner member and extend the cut as far as said apex, bending the metal therefrom to form the ears 9, said ears extending in the plane of and forming a continuation of the adjacent side or plate. These ears are preferably staggered, as shown, and are riveted to the opposite sides 7 of the reentrant angle 6 of the outer member. A sufficient number of these ears is provided to make a rigid connection between the inner and outer members. Adjacent the outer edges the inner plates 8 are provided with holes 11 opposite the holes 10 in the outer plates, whereby common fastening devices may be inserted through said plates and the box material therebetween. The lower end of the outer member may be extended below the corresponding end of the inner member to embrace and protect the adjacent portion of the box-bottom.

It will be apparent that the construction described provides an extremely effective corner-stay. The sides 7 of the reentrant angle 6 form abutments for the square ends of the side and end pieces of the box, and their length corresponds to the thickness of the material employed for such pieces. The manner of forming the ears 9 enables the members 8 to be quickly assembled and maintains an equal distance between each of the plates 8 and the opposite outer plate 2.

In Fig. 4 there is illustrated a modification of the stay shown in Figs. 1 to 3. In the construction shown in the latter figure more of the metal of the outer member 2^a is employed for forming the reentrant angle 6^a than is the case with the device shown in the other figures, and the surplus metal after forming the legs 7^a is bent at right angles to the bisector of such angle to form a flat bearing-surface 12. The apex of the inner member is similarly flattened to form a bearing-surface 13, and the said surfaces are secured together by rivets 14. As in the former modification the sides of the reentrant angle form stops for the side and end of the box.

In assembling, the stay is slipped onto the side and end of the box with the ribs 3 in engagement with the rabbets. The skirt or extension of the outer member covers and protects the adjacent portion of the bottom of the box.

Having thus described my invention, what I claim as new, and desire to secure by Letters Patent, is—

1. A corner-stay for boxes and the like comprising inner and outer sheet-metal angular members adapted to embrace the adjacent ends of the side and end pieces of a box, 5 the outer member having a reentrant angular projection the sides of which space said members apart and serve as abutments for the side and end pieces of the box, and rivets extending through the inner member and the reentrant angular projection of the outer member, substantially as specified. 10
2. A corner-stay for boxes and the like comprising inner and outer sheet-metal angular members adapted to embrace the adjacent ends of the side and end pieces of a box, 20 the outer member having a reentrant angular projection and the inner member having a corresponding outwardly-projecting angular portion, and means for securing such angular projections together, said means comprising ears bent from one of such projections and engaging opposite sides of the other projection, substantially as specified. 25
3. A corner-stay for boxes and the like comprising inner and outer sheet-metal angular members adapted to embrace the adjacent 30
- ends of the side and end pieces of a box, the outer member having a reentrant angular projection at the apex thereof opposite the apex of said inner member, and means for securing the said members together, said means comprising ears struck out from the sides of said inner member and bent into the plane of the sides of the angular projection on the outer member, and rivets extending through said ears and the sides of said projection, substantially as specified. 35
4. A corner-stay for boxes and the like comprising inner and outer sheet-metal angular members adapted to embrace the adjacent ends of the side and end pieces of a box, 40 the outer member having a reentrant angular projection extending to the inner member, and means connecting said members, the outer member extending below the inner member to form a skirt for inclosing and protecting the adjacent portion of the bottom of the box or receptacle, substantially as specified. 45

In testimony whereof I affix my signature in the presence of two witnesses.

HENRY H. DEWEY.
